US00D941876S

(12) **United States Design Patent** (10) Patent No.: **US D941,876 S**
Chaudhri et al. (45) Date of Patent: ** Jan. 25, 2022

(54) **DISPLAY SCREEN OR PORTION THEREOF
WITH GRAPHICAL USER INTERFACE**

3/04886; G06F 3/0489; H04L 12/581;
H04L 12/1813; H04L 51/32

See application file for complete search history.

(71) Applicant: **Apple Inc.**, Cupertino, CA (US)

(72) Inventors: **Imran Chaudhri**, San Francisco, CA (US); **Kevin Will Chen**, Cupertino, CA (US); **Alan C. Dye**, San Francisco, CA (US); **Dylan Ross Edwards**, San Jose, CA (US); **Christopher Foss**, San Francisco, CA (US); **David C. Graham**, Campbell, CA (US); **Aurelio Guzmán**, San Jose, CA (US); **Jonathan P. Ive**, San Francisco, CA (US); **Chanaka Karunamuni**, San Jose, CA (US); **Wan Si Wan**, Sunnyvale, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/781,712**

(22) Filed: **Apr. 30, 2021**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The broken lines in the FIGURE show a display screen or portion thereof, and form no part of the claimed design.
